UNITED STATES PATENT OFFICE

2,052,643

FIREPLACE HEATER

Arthur B. Modine, Racine, Wis., assignor to Modine Manufacturing Company, Racine, Wis., a corporation of Wisconsin

Application March 28, 1934, Serial No. 717,722

7 Claims. (Cl. 126—121)

My invention belongs to that general class of devices known as heaters, and relates more particularly to what may be termed a mechanical fireplace heater adapted to be positioned in a fireplace to heat air in the room by drawing the same from the room, passing it through the heater and discharging it back into the room.

It is well known that with the general type of fireplace in which coal, coke or wood is placed in the fireplace or on a grate therein or in gas grates or the like, the major portion of the heat is discharged up the chimney and only a portion radiated out into the room. It thus happens that a fireplace although ordinarily a thing of beauty, adding to the appearance of the room and making the same more attractive, is more or less of a failure insofar as furnishing heat is concerned. If the chimney check damper is closed to prevent the loss of heat up the chimney, the fireplace smokes and the draft is poor, while if it is only partially closed the fire may not burn so readily and less heat be radiated. Where the chimney damper is opened wide practically all of the heat is discharged up the chimney and the only value of the fireplace is the radiant heat that may be given off and its ornamental possibilities in the room. With my improved fireplace the same loses none of its ornamental value and the gases passing up the chimney have a very considerable portion of the heat units abstracted therefrom to heat air which is circulated and discharged back into the room. Consequently, it is not necessary to choke down the draft, thereby dulling the fire or retarding the escape of smoke.

In my improved device air is taken from the room, thoroughly heated and discharged back into the room under forced draft, without in any way interfering with the chimney draft. The chimney draft, however, will be cooler and less heat is wasted. The air may be moistened or humidified as desired. The invention has among its objects the production of a device of the kind described that is simple, compact, inexpensive, attractive, durable, efficient and satisfactory for use wherever found applicable.

It has particularly as an object the production of a device that will promote the building of fireplaces with all the advantages thereof and at the same time permit the efficient, economical and comfortable heating of the room at all times.

Many other objects and advantages of the construction herein shown and described will be obvious to those skilled in the art from the disclosure herein given.

To this end my invention consists in the novel

construction, arrangement and combination of parts herein shown and described, and more particularly pointed out in the claims.

In the drawings, wherein like reference characters indicate like or corresponding parts:

Fig. 1 is a perspective view of one embodiment of the invention;

Fig. 2 is a plan view of the same;

Fig. 3 is a front elevation of the device;

Fig. 4 is a sectional view taken substantially on line 4—4 of Fig. 3;

Fig. 5 is a perspective view of another embodiment of the invention illustrating a slightly modified form; and

Fig. 6 is a vertical cross-sectional view taken 15 through the flues on line 6—6 of Fig. 5.

My device is intended to be positioned in a fireplace and serve as a grate for the burning of wood, coal, coke or the like, or to be used in connection with gas, oil, electricity or other sources 20 of heat. As shown, the same consists of a pair of supports or standards 1 and 2 which are tubular or chambered, the two standards being connected with tubes or flues 3 which communicate with the chambers in the standards. These tubes 25 or flues 3 may be of any desired shape in cross-section, either cylindrical as shown, elliptical, rectangular or otherwise, and are arranged above the grate 4 preferably near the top of the standard and at the rear of the device. They may be 30 provided with fins, flutes or other equivalent devices. In Figs. 1 and 2 I have shown one tube provided with fins 3'. The grate 4 may be of any suitable type, this depending to a large extent 35 upon the material to be burned.

The standards are provided with supporting legs 5 and may be provided with spacers and securing means in the shape of rods or bolts 6—6 extending from side to side of the device. As shown, the grate 4, in this particular embodiment 40 of the invention, is provided with an upwardly extending part 4' and the grate hung or supported from the rods 6—6 at the front and back (see Fig. 4). A plate 9 may also be provided to additionally support the grate. The rear end of the 45 grate is therefore supported by the engagement of the turned-over portion 10 of the part 4' and the rear plate 9 so that it is capable of supporting the fuel without sagging.

One of the standards, as shown 1, is provided 50 with an air intake and the other with an air discharge outlet. As shown, 8 represents a housing provided with an air opening 11 or inlet communicating with the chamber 7 in the standard. The housing is arranged to contain a fan 12 of 55

suitable size, shape and design driven by an electric motor 13 or equivalent means, air being drawn into the housing by the fan. This induces a circulation of air through the device which passes up 5 through the chamber 7 and is heated to some extent, and through the tubes or flues 3, where it is further heated, into the chamber in the standard 2 from whence it is discharged through the outlet at 19 into the room. The motor may be of constant speed or any of the well known controlling 10 devices may be applied so as to permit control of the speed and vary the amount of air circulated through and heated by the device. Obviously, air passing through the device is heated from the burning gas or fuel, instead of passing up the chimney as waste heat, and is utilized to effectively heat the room and it may be mentioned that owing to the forced circulation, the room is thoroughly heated throughout as distinguished 15 from the ordinary fireplace where the room is heated only from the radiated heat.

I have shown the standard 2 provided with the water pan 14, within which is arranged a pad 15 which may be moistened by means of the pipe 16. When it is desired to have the device also serve as a humidifier and prevent the heated air from becoming too dry, water may be placed in the pan or the pad used and the pad moistened. 20 As most clearly shown in Figs. 1 and 3, I also provide louvres 17 at the discharge outlet 19. These form a grille and add to the attractiveness of the device, and by making them adjustable it is possible to direct the flow of air up or down as 25 desired.

In the device shown in Figs. 5 and 6, which is a simplified construction, the same general features are embodied in the device, this design rendering itself readily applicable to sheet metal construction. Referring to these figures, 41 and 30 42 represent standards which are chambered and communicate with the flues 43. The device is shown provided with a grate 44 and with bottom and back plates 45 and 46, respectively. In this case the air is taken in through an opening 47 at 35 the side of standard 41 and circulated by means of the fan 48 driven by motor 49. The same passes through the chamber 50 through the flues and into chamber 51 from whence it is discharged through the opening 52. I have shown in Fig. 5 40 a representation of a portion of a fireplace F showing the installation of the device in the fireplace. The device shown in Figs. 1 to 4 may be similarly positioned, it being obvious that it is not necessary to rebuild the fireplace to receive 45 the unit.

I have also shown this embodiment of the invention provided with the plates 53 which serve as a grille and which may be adjusted to direct the air as desired. The device is also shown with 50 a humidifying pan 54 and filler pipe 55 similar to the construction previously described.

Having thus described my invention, it is obvious that various immaterial modifications may be made in the same without departing from the 55 spirit of my invention; hence I do not wish to be understood as limiting myself to the exact form, construction, arrangement and combination of parts herein shown and described, or uses mentioned.

70 What I claim as new and desire to secure by Letters Patent is:

1. A portable fire-place heater adapted to be positioned in a fire-place recess and consisting of a pair of spaced chambered standards, flues 75 extending between said standards and com-

municating with the chambers therein, a grate interposed between the standards and providing a fuel receptacle open at its top and front sides, means for causing a circulation of air into one standard through the flues and out of the other standard adjacent the floor level at the front side thereof, and means in one of said standards for moistening said air prior to its discharge from the heater. 5

2. A portable fireplace heater adapted to be 10 positioned in a fire-place recess and consisting of a pair of spaced chambered standards, flues extending between said standards and communicating with the chambers therein adjacent the upper portion thereof, a grate interposed between 15 the standards and providing a fuel receptacle open at its top and front sides, means for causing a circulation of air into the lower portion of one standard through the flues and out of the other standard from adjacent the lower front side 20 thereof, and adjustable means in said other standard for regulating the angle of air discharge from the heater.

3. A portable fire-place heater adapted to be 25 positioned in a fire-place recess and consisting of a pair of spaced chambered standards, flues extending between said standards and communicating with the chambers therein, a grate interposed between the standards and providing a fuel receptacle open at its top and front sides, means for 30 causing a circulation of air into one standard through the flues and out of the other standard from adjacent the floor level at the front side thereof, means for moistening said air prior to its discharge from the heater, and adjustable means for regulating the angle of air discharge 35 from the heater.

4. A heater adapted to be positioned in a fire-place, comprising a portable unit consisting of a grate providing a fuel receptacle open at its front 40 and top sides, chambered supports for said grate arranged at the ends thereof, flues communicating with the interior of said supports and extending above said grate, one of said supports provided with an air inlet adjacent its front side 45 and with means for forcing air therethrough into the support and through said flues and other support, said last-mentioned support being provided with an opening adjacent the floor level 50 for the discharge of air forwardly therefrom, and adjustable means adjacent said discharge opening for controlling the direction of flow of the air therethrough.

5. A portable fire-place heater adapted to be 55 positioned in a fire-place recess and consisting of a pair of spaced chambered standards having inlet and discharge openings formed therein adjacent the floor level, respectively, flues extending between said standards and communicating with the chambers therein, one of said flues being 60 provided with fins, a grate interposed between the standards and providing a fuel receptacle open at its top and front sides, a fan adjacent said inlet provided with driving means for causing a circulation of air into one standard through 65 the flues and out the discharge opening of the other standard, means for moistening said air prior to its discharge from the heater, and means for controlling the angle of air discharge from 70 said other standard.

6. In a heater adapted to be positioned in a fire-place recess, a portable unit consisting of a grate providing a fuel receptacle open at its front and top sides, supports for said grate consisting 75 of standards arranged at the ends thereof and

provided with chambers therein, flues extending between the standards and communicating with said chambers and extending above said grate, one of said standards being provided with an air inlet adjacent its front side, means for inducing a circulation of air therethrough into the support and through said flues and other support, said last mentioned support provided with an outlet adjacent the floor level for the discharge of air therefrom.

5. 7. A portable fire-place heater adapted for positioning in a fire-place recess and comprising a

pair of chambered end standards, tubular air flues extending between and communicating with the chambers in said standards, a grate interposed between and carried by the standards in a plane below said flues and providing a fuel receptacle open at its top and front sides, one of said standards having an inlet for admitting air thereto, and the other of said standards having an outlet adjacent the floor level for discharging air therefrom.

ARTHUR B. MODINE.
